HANGER IN STRIP FORM

Ivor B. Watts, Nutley, N. J.

Application October 19, 1948, Serial No. 55,339

1 Claim. (Cl. 211—113)

1

This invention relates to a support for hanging articles and more particularly to a molded support in which hooks or other means of engaging articles may be adjustably spaced at regular intervals.

An object of this invention is to provide a rack of molded composition having suspending devices by which articles may be supported in desired arrangement.

Another object of this invention is to provide a molded rack in which the suspending devices are easily moved and supported by a ball and socket pivot providing them with a freedom of motion.

A still further object of this invention is to provide a molded rack which is open on the upper side for simple fabrication but has a rigid construction.

These and other objects of this invention will become more apparent upon consideration of the following description taken with the drawings in which

Fig. 1 is a side elevation view of supporting members of this invention one of which is in section;

Fig. 2 is a transverse section of Fig. 1 taken on line II—II of Fig. 1;

Fig. 3 is an elevational view of supporting members of this invention from below and attached to a surface;

Fig. 4 is a transverse section of Fig. 1 taken on line IV—IV and showing the lug members in section;

Fig. 5 is a top view of a modification of the supporting member of this invention showing the recess and ball sockets within the supporting member; and

Fig. 6 is a transverse section of Fig. 5 taken on line VI—VI

In general the supporting means of this invention comprises an elongated molded article which is provided with a large recess in its upper surface and a relatively narrow slot opening extending from the larger recess through the lower surface of the article. In the bottom of the large recess are formed a series of small recesses or sockets at regular intervals. The upper end of the hook or other article-engaging means is formed to fit into the small recesses and be retained there but with a freedom of movement.

With reference to Fig. 1 two molded strip sections 10 are attached to the under side 11 of a shelf. Each strip 10 is formed with a large hollow in its upper surface providing a central recess 12 which runs longitudinally for substantially the entire length of the strip 10 and has

an opening 13 at the top and is closed at each end by walls 14. The strip 10 is provided with a slot 16 which is centrally located along the bottom of the central recess 12 and extends from the recess 5 12 through the strip 10 as shown in Fig. 4. The strip member 10 is fastened to the surface 11 by screws or bolts 24 through lug members 27 on each side of the strip. As shown in Fig. 3, these are positioned to provide structural strength to 10 the strip member 10 in securing the sides of the strip from spreading and preventing the slot 16 from widening. The slot 16 runs longitudinally of the strip 10 and hooks 17 extending through the slot 16 from the central recess are movable 15 between edges 22 of the slot 16 through the length of the strip 10. In the embodiment shown in Figs. 1 and 3 the hooks 17 are introduced into the slot 16 and central recess 12 through a port 18 provided at one end of the slot 16, these hooks 17 20 being formed into a hook portion 23 and a hemispherical ball end 21 having a flat top surface 33. The hook portion 23 extends through the slot 16 to engage the suspended articles and the semi-ball end 21 is retained in the recess 12 between the edges 22 of the slot 16.

Sockets 19 are molded at regular intervals in the inner surface of the recess 12 along the slot 16. These sockets are formed to receive the semi-ball ends 21 molded on the upper end of the hooks 17. The end 21 of a hook 17 is inserted into the central recess 12 through port 18 and is moved longitudinally into engagement with edges 22 of the slot 16 which is narrow enough to engage the ball end 21 while permitting the hook portion 23 to extend below the strip member 10. The sockets 19 molded in the strip 10 and the ball ends 21 molded on the hooks 17 are provided to engage in a pivoting ball and socket joint which retains the hook in its position in the slot 16 30 against longitudinal and lateral movement but permits rotation on its perpendicular axis and pivoting of the hook 17 in this fixed position. At the same time the hooks 17 held in the ball and socket joints by the weight of the hooks or the articles hung thereon are readily disengaged vertically for longitudinal rearrangement.

The slotted strip 10 may be closed at both ends as shown in Figs. 1 and 3 and fastened to the shelves 11 by screws or bolts 24 through lug members 27 on each side. In the modification of the strip member 10 shown in Fig. 5 the strip 10 is molded with one end of the slot 16 closed by the wall 14 and the other end formed into an open end 29 for receiving the hooks 17. To provide 40 45 structural strength and rigidity to this modifica-

tion of strip 10 a brace 26 is molded into the strip 10 across the top of the recess 12 with flanges 37 extending into the strip 10 to join the sides together and prevent widening of the slot by spreading of the strip sides as shown in Fig. 6.

The recess 12 is provided with a pair of shoulders 28 on each of the edges 22 adjacent the port 16 in the embodiment of Figs. 1 and 2 or the open end of the slot 29 in the modification of Fig. 5. These shoulders 28 are molded into the strip 10 to provide a passage 31 between upper surface 32 of the shoulders 28 and the surface 11 to which the strip member 10 is attached. This passage 31 is designed to cooperate with the hemispherical shape of the ball end 21 so that the flat upper surface 33 of the ball end 21 when passed horizontally along the surface 11 permits the ball end 21 to pass over the shoulders 28 and into the recess 12. However, the clearance of passage 32 is formed to be sufficiently small to insure against the accidental or unintentional removal of a hook from slot 16 by jamming the ball end 21 if the surface 33 is not held horizontal to the surface 11 as the hook 17 passes the shoulders 28.

As shown in Figs. 1 and 3 several of the strip members 10 may be placed end to end providing a line of article-supporting members in demountable sections.

The strip member 10 of this invention may be readily formed from any moldable composition and is advantageous in providing a shape which is readily molded. The large opening at the upper side of the recess 12 permits the strip member 10 of this invention to be formed by a simple and inexpensive molding operation. Another advantage of this invention is that the sockets 19 are easily formed in the molding operation which makes the strip member.

It will be apparent to those skilled in the art that various modifications can be made without departing from the principles of this invention as disclosed herein, and for that reason it is not intended that it should be limited other than by the scope of the appended claim.

Having thus described my invention what is claimed as novel is:

In a device for supporting suspended articles, an elongated supporting strip of molded material having means for attaching it to the under side of a shelf and formed with a hollow recess open at the top and extending longitudinally of said strip and exposing the said underside of said shelf, a relatively narrow slot opening downward from said recess, suspending members having shank portions adapted to slide in said slot and enlarged rounded end portions retained in said hollow recess by engagement with the walls thereof adjacent said slot, a series of evenly spaced rounded sockets formed in the bottom of said recess to receive said enlarged ends of said suspending members, an opening in said strip between the ends thereof formed to permit insertion of said enlarged end portions of said suspending members into said hollow recess and removal of said enlarged end portions therefrom, and shoulder members on the wall positioned between said opening and said series of sockets formed to selectively pass said shaped enlarged ends.

IVOR B. WATTS.
